Primary Examiner—Dominic Simone

(74) Attorney, Agent, or Firm—Michael E. Zall

(57) **CLAIM**

I claim the ornamental design for the shoe lace cover, as shown and described.

DESCRIPTION

FIG. 1 is a front perspective view from the right side showing my new shoelace cover design;

FIG. 2 is a front view thereof;

FIG. 3 is a back view thereof;

FIG. 4 is a top view thereof; and

FIG. 5 is a bottom view thereof.

FIG. 6 is a left side view thereof;

FIG. 7 is a right side view;

FIG. 8 a rear perspective view thereof; and,

FIG. 9 is a perspective view of the shoe lace cover in use on an athletic shoe, (shown in broken lines), the shoe forming no part of the design to be patented.
